(57) CLAIM

The ornamental design for a shoulder wrap for applying cooling and compression, as shown and described.

DESCRIPTION

FIG. 1 is a perspective view of a shoulder wrap for applying cooling and compression showing our new design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof;

FIG. 8 is a rear view of a second embodiment of the shoulder wrap for applying cooling and compression; and,

FIG. 9 is a left side view thereof.

The broken line showing in FIGS. 8 and 9 is for illustrative purposes only and forms no part of the claimed design.
